[57] CLAIM

The ornamental design for the visual indicating electronic output tester, as shown and described.

DESCRIPTION

FIG. 1 is a top plan view of my visual indicating electronic output tester showing my new design;
FIG. 2 is a side elevation view thereof;

FIG. 3 is a bottom plan view thereof;

FIG. 4 is a left end elevational view thereof;

FIG. 5 is a right end elevational view thereof; and

FIG. 6 is a side elevation view thereof the closed and in retracted position.
